REFRIGERATING APPARATUS

Joseph E. Harris and Walter L. Frey,
Stayton, Oreg.

Application December 21, 1939, Serial No. 310,424

1 Claim. (Cl. 62—91.5)

This invention relates to refrigeration and particularly to a means for circulating a refrigerated current of water, brine or fluid in which gas, due to the volatilization of the refrigerating medium is utilized to cause the circulation of the refrigerated fluid so that the refrigerated fluid is delivered to a tank or receptacle and thereafter the said fluid is again circulated through the receptacle containing the refrigerant so that the refrigerated fluid is kept in circulation.

It is an object of this invention to utilize the gases and pressure developed from the volatilization of "dry ice" to effect the said circulation, as stated.

It is a further object of this invention to provide a receptacle for the "dry ice" which has an airtight construction except for a vent or discharge pipe through which the gases escape, it being understood that sufficient pressure will develop within the said receptacle to circulate the refrigerated fluid.

It is an object of the invention furthermore to provide an arrangement of parts and a combination of elements operative to produce the result stated and the parts of which are simple in construction and comparatively inexpensive to operate and maintain.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which—

Figure 1 illustrates a view in elevation, partly in section of an apparatus embodying the invention;

Figure 2 illustrates a horizontal sectional view of the "dry ice" receptacle showing in plan the circulating pipes;

Figure 3 illustrates a sectional view of the injector used in the system; and

Figure 4 illustrates a sectional view of a fragment of the ice chamber showing the connection of the pipe through the side thereof.

In the drawing 5 denotes a receptacle for containing "dry ice" and it has a cover 6 attached to a flange 7 thereof by fastenings 8 such as screws or the like, although ordinary clamps might be employed for holding the cover which should have an airtight joint with the flanges 7. The receptacle has a pipe 9 connected to it 55

which communicates with the interior of the receptacle and the said pipe may have a check valve 10, a manually operated valve or thermostat 11 and a safety valve 12, by which the gas escaping from the receptacle 6 may be controlled. 5 A tank or receptacle 13 is preferably supported in any appropriate manner with its bottom above the plane of the bottom of the receptacle 5. A coil 14 is located in the receptacle 5, preferably at the bottom thereof, so that the "dry ice" 15 in the receptacle 5 will be supported by the coil, although the coil, of course, may be embedded in the mass of "dry ice." In any event, the fluid in the coil is cooled and circulation of the cooled fluid is accomplished through the employment of the gas pressure escaping through the pipe 9, and it is shown that the said pipe 9 communicates with a chamber 16 of enlarged area or capacity as compared with the said pipe 9, so that the gas 15 which escapes from the pipe 9 causes the injection of the refrigerated fluid which also enters the chamber through the pipe 17 which is a part of the circulating system including the coil 14.

The pipe 18, which is also a part of the circulating system, is attached to the bottom of the receptacle 13 and communicates therewith, preferably through the bottom of said receptacle. Hence, it is seen that as the refrigerated fluid passes from the coil through the pipe 17 to the chamber 16, the gas escaping from the receptacle 5 acts to force the refrigerated fluid into the tank 13 through the nipple or pipe 19, which communicates with the said tank 13 through its bottom or otherwise, so that a circulating system is produced whereby the refrigerated fluid is delivered to the tank and is then permitted to gravitate therefrom through the coil for a repetition of the circulation and operation.

The pipe 9 is guarded by a screen 9a to prevent 40 the entrance of dust or foreign substances which might choke the injector, although a screen for the purpose may be provided at any convenient location.

We claim:

45 In a refrigerating apparatus, a receptacle for containing a volatilizable refrigerant, pipes for the circulation of refrigerated fluid having a connecting coil, the said coil being located in the said receptacle under the influence of the refrigerant, a fluid receptacle remote from the first mentioned receptacle and having its bottom on a plane above the coil, one of the said pipes communicating with the interior of the second mentioned receptacle through the bottom thereof, whereby the fluid in the second mentioned recep-

tacle gravitates through the said coil, a chamber with which the other pipe communicates, the said chamber having a connection with the second mentioned receptacle through its bottom, a pipe connected to the interior of the first mentioned receptacle for conveying gas under pressure due to the volatilization of the refrigerant,

5

the said pipe extending into the chamber and forming an injector for forcing fluid entering the said chamber through the pipe of the said coil into the second mentioned receptacle.
